HOIST SAFETY DEVICE

Edward O. Hermann, Mill Valley, Calif.

Application May 18, 1948, Serial No. 27,741

7 Claims. (Cl. 187—77)

1

This invention relates to a hoist safety device for use during hoisting or lowering of a load by cables, jacks or the like, which is adapted to provide support for the load in the event of failure of the hoisting apparatus.

In hoisting and lowering loads, as, for example, in hoisting automobiles on auto racks in freight cars and in lowering the same at the point of destination, it is desirable to provide emergency support for the load in the event of failure of the hoisting apparatus. Such emergency support is desirably operable to provide support both during hoisting and lowering, and it is also desirable that it be actuated only in the event of a sudden dropping of the load so as not to interfere with normal hoisting or lowering thereof. Safety supports for this purpose heretofore in use are makeshift, do not provide support at all times when needed, or require considerable man-power in their handling.

It is an object of the invention to provide an improved hoist safety device.

It is a further object of the invention to provide a hoist safety device which is operative to provide support for loads, both during hoisting and lowering of the same, in the event of failure of the hoisting apparatus.

It is a still further object of the invention to provide a hoist safety device which is adapted to use either as a separate, transportable device which can be used wherever needed, or which can be installed as a permanent fixture in a freight car, on a loading platform, or wherever else it may be desired.

It is a particular object of the invention to provide a hoist safety device for use in conjunction with auto racks in freight cars fulfilling several or all of the desiderata detailed hereinabove.

These and other objects of the invention will be better understood by reference to the ensuing description and the appended claims.

One form which the invention may assume is exemplified in the following description and illustrated by way of example in the accompanying drawings, in which:

Fig. 1 is a front view, partly in elevation and partly in cross-section.

Fig. 2 is a side view, otherwise similar to Fig. 1.

Fig. 3 is a front elevation showing concealed mechanically operable parts in broken lines and in a different operative position than shown in Fig. 1.

Fig. 4 illustrates diagrammatically how the device of the invention may be used as a movable hoist support.

Fig. 5 illustrates diagrammatically how the device of the invention may be used as a permanent fixture, as in a freight car.

Referring now to the drawings, and more particularly to Figs. 1 and 2, a load is indicated at 1, such, for example, as the angle of a conventional auto frame rack used to hoist and support

2

an automobile in a freight car. Emergency support for the load, in the event of failure of the hoisting apparatus, is provided by means of a column 2 and a mechanism generally designated as 3. As shown, the column 2 is provided with opposing sets of rack teeth 4, and the column is of relatively large transverse dimensions so as to be capable of supporting a large load under compression.

10 The mechanism 3 comprises a box 10 serving both as a closure for the working parts of the mechanism and as a framework for their support. As shown, the box 10 is provided with upper and lower openings 11 and 12 adapted to receive the column 2 and to allow free movement of the box up and down the column. Disposed within the box, near the bottom thereof, is a base or casting 13 having a central opening 14 adapted to receive the column 2 and to allow free movement of the base up and down the column. The base 13 is supported upon coil springs 15, which are normally under a degree of compression determined by the weight of the base 13 and elements supported thereby and which rest upon the floor of the box. A pair of emergency supporting pawls 16 having teeth or fingers 17 adapted to engage the rack teeth 4 of the column, are provided on opposite sides of the column, each such pawl being pivotally supported upon a shaft 18 carried in bearings 19 which are suitably secured to the side walls of the box 10. The lower end of each pawl 16 is connected to a link 25 by means of a joint 26, and the inner end of each link 25 is pivotally connected at 27 to a shaft 28 carried in brackets 28a extending upwardly from and integral with the base 13. Also, each pawl is urged inwardly, that is, so as to engage its fingers with the rack teeth 4 of the column 2, by a coil spring 29 received within a socket 30 formed in the pawl and compressed between the pawl and the end wall of the box. It will be understood that each of the coil springs 15 and 29 may be anchored by any suitable means to prevent accidental displacement.

45 A cam 31 pivotally and eccentrically supported upon a shaft 32, and a roller 33 mounted on a shaft 34 carried in brackets 35, are provided for the purpose of manually actuating the supporting pawls 16 in the manner and for a purpose hereinafter described. The shaft 32 extends through and outwardly of the front wall of the box, and to its outer end is secured a lever or crank 40 having an arrow-shaped head 40a serving as a pointer for a purpose explained hereinafter.

50 55 A pair of escape pawls 41, each having a finger 41a, are also provided on opposite sides of the column. Each such escape pawl is pivotally supported upon a shaft 42 carried in bearings 43 suitably anchored in the side walls of the box 10, and the lower end of each escape pawl 41 is pivotally connected at 44 to a link 45, the other end of which is pivotally connected to a pendulum 46. The pendulum 46 is pivotally supported at

47 by a pendulum support 48, which in turn is supported for linear and angular movement by means of a shaft 48a carried in a bearing 51 suitably anchored in the front wall of the box 10 and received within a slot 49 formed in the top of the pendulum support, and by means of a pivotal connection 50 with the center of the cam 31.

The mechanism is further provided with a plunger 55 secured to or integral with the base 13. The plunger 55 extends upwardly through an opening 56 formed in the top of the box 10, and it is provided with a support bracket or foot member 57 at its upper end above the box. Also, the mechanism is provided with a chain and hook 58 for a purpose described hereinafter.

The device as thus far described operates as follows: Referring to Fig. 4, and assuming it is desired to provide support during lowering an automobile (not shown) supported on a standard auto rack 1 in a freight car, a column 2 will be positioned on each side of the freight car and at the front end of the rack, as shown. Support for the columns 2 may be provided by means of blocks 60 secured to the floor 61 of the freight car, and by engaging the top of each column with brackets (not shown) at the top of the freight car, such brackets being well known, standard equipment.

Next, each box 10 is elevated to the position shown, with the bracket 57 adjacent the load and with the pointer 40a directed downward. The various pawls and links will then be in the positions shown in Fig. 1, in which, it will be noted, the supporting pawls 16 are held out of engagement with the rack teeth 4 of the column. As the load is lowered, a downward force is exerted on whichever of the escape pawls 41 is in contact with a rack tooth of the column. The shape of the fingers 41a on the escape pawls is such that by engaging the rack teeth 4 on the column, either pawl will support the weight of the box and its associated elements at any desired position on the column. However, the added weight of a load, as the same is lowered, is sufficient to displace or rock whichever pawl is in contact with the rack teeth, thus rocking the pendulum 46. It will thus be seen that the pendulum 46 and escape pawls 41 will oscillate and will thus cause the box 10 to travel downwardly along the column at the rate of lowering the load. The pendulum is effective, by reason of its period of oscillation, to control the rate of travel of the box down the column. Preferably, a short pendulum having a short period is employed, thus rapidly accommodating the rate of travel of the box to changes in the rate of lowering of the load.

Should the hoisting mechanism fail, the resultant sudden lowering of the load upon the bracket 57 and plunger 55 will thrust the base 13 downwardly, compressing the springs 15. This will result in actuating the support pawls 16 so as to engage the same with the rack teeth 4 of the column, as shown in Fig. 3. Sufficient support is thus provided almost immediately to prevent further falling of the load.

Assuming now that it is desired to provide emergency support for the load during hoisting of the same, the chain and hook 58 are engaged with the load and the pointer 40a is moved into upward position as shown in Fig. 3. This movement of the pointer will rotate the cam 31 which, bearing against the roller 33, will depress the base 13 and compress the coil springs 15, as

shown in Fig. 3, thus engaging the support pawls 16 with the rack teeth 4 of the column. It will also be seen that such movement of the cam through 180° will also rotate the pivot point 50 of the pendulum support 48 through an equal angle, thus displacing the pendulum support downwardly and actuating the escape pawls 41 through the medium of the links 45 so as to completely disengage them from the rack teeth 4 of the column. The support pawls 16 are meanwhile held by the coil springs 29 firmly in engagement with the rack teeth of the column, so as to prevent falling of the load in the event of failure of the hoisting apparatus. As the load is hoisted, the box 10 will follow it up the column since it is secured to the load by the chain and hook 58. The upward force exerted on the load by the hoisting mechanism will disengage the support pawls 16 from the rack teeth 4 sufficiently to allow upward travel of the box, but at all times support is provided in the event of sudden falling of the load.

Referring again to Figs. 1 and 2, an auxiliary feature may be provided, if desired, to ensure that the escape levers 41 will support the weight of the box 10 and elements associated therewith when the box is not under an added load. This auxiliary feature comprises a lever 70 pivotally supported at 71, as shown, having a weight 72 depending therefrom and overlying the pendulum 46 and normally pivoted out of engagement with the pendulum by a coil spring 73 compressed between the opposite end of the lever and the top of the box 10. A rod 74 reciprocably disposed within the plunger 55 is thrust upwardly by a coil spring 75 disposed within a recess in the plunger 55, such that its upper end projects above the bracket 57 and a pin 77 projecting from the rod pivots the lever 70 against the tension of coil spring 73 so as to press the weight 72 against the pendulum 46, thus preventing it from oscillating. However, when a load is imposed on the bracket 57, as during lowering of a load, the rod 74 is depressed, thus disengaging the pin 77 from the lever 70 and allowing the pendulum and support pawls to operate.

Referring now to Fig. 5, the device of the invention is shown adapted to use as a permanent car fixture. The column 2 is secured to the floor 61 and roof 80 of a freight car, and it is inverted, with the rack teeth 4 in reverse position as compared with the position shown in Fig. 1. The column 2 may also be of smaller dimensions, as indicated, since it is under tension rather than compression. The box 10, shown diagrammatically, is also inverted, and the auxiliary features identified as 70 to 77 are omitted; otherwise, the box 10 and the elements associated therewith are identical with the structure 3 shown in Figs. 1 and 2.

In this embodiment or adaption of the invention, a cable 81 is provided. The cable 81 is secured at one end to the load 1, is trained over a pulley 82 secured at or near the roof 80 of the freight car as shown, passes through appropriate openings (not shown) in the box structure and is secured at its other end to a counterweight 83 abutting the bracket 57 at the lower end of the plunger 55.

In operation, the adaptation shown in Fig. 5 functions similarly to that shown in Figs. 1 to 4, except that the box 10 and counterweight 83 move oppositely to the load. On failure of the load during lowering, the counterweight 83 is raised by the cable 81, thus compressing the

coil springs 15 and engaging the support pawls 16 with the rack teeth 4. Desirably, in this adaptation of the device, the coil springs 15 are somewhat larger and stronger than in the movable device of Figs. 1 to 4. It will be understood, of course, that the cable 81 does not normally carry a load except for the weight of the box 10 and counterweight 83.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A hoist safety device comprising a main load supporting member adapted to rest upon and support a load above a floor, a frame movable longitudinally of said main member, an auxiliary load supporting member pivotally supported by said frame and pivotable into and out of engagement with said main member, co-engaging means on said main and auxiliary members adapted to lock the members together when said co-engaging members are in engagement, resilient means for actuating said auxiliary member, said resilient means being such as to pivot said auxiliary member into engagement with the main member on compression thereof, means responsive to sudden lowering of the load operative to compress said resilient means and oscillatory means for restricting the rate of downward movement of said frame.

2. A hoist safety device comprising a load supporting column having a rack disposed longitudinally thereof, a frame movable longitudinally of said column, a pawl pivotally supported by said frame for pivotal movement into and out of engagement with said rack, resilient means supported by said frame, means connecting said resilient means and pawl for pivotal movement of the pawl into and out of engagement with said rack upon compression and expansion, respectively, of the resilient means, means responsive to a sudden lowering of the load for compressing said resilient means and oscillatory means for restricting the rate of downward movement of said frame.

3. A hoist safety device comprising a load supporting column having a rack disposed longitudinally thereof, a frame, a pawl pivotally supported by said frame for movement into and out of engagement with said rack, resilient means supported by the frame, means connecting said resilient means and pawl for pivoting said pawl into and out of engagement with said rack upon compression and expansion, respectively, of the resilient means, means responsive to a sudden lowering of the load for compressing said resilient means, and independent means for compressing said resilient means comprising a member eccentrically and pivotally supported by said frame and adapted in one angular position to compress and in another angular position to release compression of said resilient means.

4. A hoist safety device comprising a load supporting column having a rack disposed longitudinally thereof, a frame, a pawl pivotally supported by said frame for movement into and out of engagement with said rack, a coil spring supported by the frame, a rigid member supported by said coil spring and free to move relatively to said frame and longitudinally of said column upon compression and expansion of said spring, said

rigid member being provided with a longitudinal member adapted to bear against a load, and a link connecting said rigid member and said pawl for pivotal movement of said pawl into engagement with said rack upon compression of said spring.

5. A hoist safety device comprising a vertically disposed rack adapted to support a load, a frame movable longitudinally of said rack, a pawl pivotally supported by said frame for pivotal movement into and out of engagement with said rack, resilient means for pivoting said pawl into and out of engagement with said rack on compression and expansion, respectively, of the resilient means, means responsive to sudden lowering of the load for compressing said resilient means, independent means for compressing said resilient means, and other resilient means for holding said pawl yieldably in engagement with said rack.

20 6. In a hoist safety device comprising a rack adapted to be positioned vertically and to support a load when in vertical position, a frame, a pawl pivotally supported by the frame for pivotal movement into and out of engagement with said rack, and means responsive to load pressure for pivoting said pawl into engagement with said rack but normally holding said pawl out of engagement therewith except in response to sudden lowering of the load, the improvement which comprises a second pawl pivotally supported for movement into and out of engagement with said rack, said second pawl being such as to support the weight of said frame and elements supported thereby upon said rack when in engagement therewith but such as to be rocked out of engagement by the added weight of a load, and a pendulum supported for oscillatory movement and connected to said second pawl, said pendulum being operable to return said second pawl to rack-engaging position.

35 7. In a hoist safety device comprising a vertical rack having two opposed sets of rack teeth on two sides thereof, a frame, a first pawl pivotally supported by said frame for movement into and out of engagement with said rack, resilient means operable to engage and disengage said first pawl with said rack upon compression and expansion, respectively, of said resilient means, and means responsive to a sudden lowering of the load operable to compress said resilient means, the improvement which comprises an escapement mechanism for supporting the weight of said frame and elements supported thereby at any desired level on said rack, but allowing downward movement thereof relative to the rack in response to lowering of a load, said mechanism comprising a pair of opposed escape pawls each pivotally supported to move into and out of engaging position with respect to one of said sets of rack teeth, each said escape pawl being adapted when in engaging position to support said weight but such as to rock out of said position under an added load, and a pendulum supported for oscillatory movement and pivotally connected to each escape pawl to control the rate of movement of said frame relative to said rack.
